UNITED STATES PATENT OFFICE.

FRED H. RUNDELL, OF HORSEHEADS, NEW YORK.

CHOPPING-KNIFE.

SPECIFICATION forming part of Letters Patent No. 518,279, dated April 17, 1894.

Application filed July 28, 1893. Serial No. 481,710. (No model.)

To all whom it may concern:

Be it known that I, FRED H. RUNDELL, of Horseheads, in the county of Chemung, in the State of New York, have invented new and 5 useful Improvements in Chopping-Knives, of which the following, taken in connection with the accompanying drawings, is a full, clear, and exact description.

My invention relates to chopping knives, 10 and has particular reference to self-cleaning knives, which may be constructed in knock-down shape, if desired. I have found by experience and practice that better results are obtained by knives having multiple blades, 15 and that the best results are obtained by constructing the blades so as to meet or cross each other at a point removed from the center, or in other words to avoid having the blades meet at a common center so as to prevent clogging, and to that end my invention 20 consists in the several new and novel features of construction hereinafter described, and which are specifically set forth in the claims thereunto annexed. It is constructed 25 as follows, reference being had to the accompanying drawings, in which—

Figure 1 is an isometrical elevation of a 30 knife complete. Fig. 2. is a bottom view thereof. Fig. 3. is a view of the main blade detached. Fig. 4. is a view of one of the auxiliary blades detached. Fig. 5. is a view of a slotted plate inclosing the upper ends of the 35 blades. Fig. 6. is a view of a bolt or screw by which the assembled blades are held to the handle.

Similar letters of reference indicate corresponding parts.

A. is the main blade constructed substantially as shown preferably having its cutting 40 edge convex and provided with substantially vertical slot ways —a— in its lower edge, and provided with a recess —b— at its upper end, the lower end of said slot way being enlarged as shown at —c— creating shoulders —d— and having the upwardly extending part —e—.

B. are auxiliary blades constructed substantially similar to the blade —A— except that there are no slot ways —a— and is provided with a slot way —f— opening from the 50 recess —b— as shown in Fig. 4. The blade —B— is then preferably bent, centrally, as

shown in the bottom view thereof in Fig. 2. The auxiliary blade —B— is then mounted upon the blade —A— by inserting the blade —A— at a point where the slot ways —a— are located, by passing the blade —A— down through the slot way —f— in the blade —B— the slot-way —a— passing over the lower portion —g— of the blade —B— directly below the slot-way —f— until their lower faces are 55 in substantially the same plain, as shown in Fig. 1.

It will not be necessary to describe the other auxiliary blade as they are both screwed upon the main blade —A— in the 60 same way.

C. is a disk or centrally perforated washer as shown in Fig. 5, having radial slot-ways —h— and adapted to fit over the upwardly extending portions —e— of the blades —A— 65 and B.

D. is a threaded bolt or screw, having one end enlarged as shown at —i—.

E. is the handle preferably of the form shown in Fig. 1 although it may be of any 70 other form desired, having a threaded central opening —j— and its lower face recessed (not shown) so as to allow the base of the handle to fit down over the extended portions —e— and rest upon the upper end of 75 the blades.

When the blades have been assembled as above described, the bolt or screw —D— is then inserted vertically in the recess —b— the head —i— passing into the enlarged portion —c— thereby allowing the head of the bolt —i— to engage with the shoulder —d— in the blades. The disk —C— is then placed over the top of the blades so that the parts —e— will pass into the slot-ways —h—; the 80 handle —E— is then screwed on or otherwise secured to the upper end of the bolt —D— when the knife is ready for use.

What I claim is—

1. A chopping knife comprising a main 90 blade having two substantially vertical slot-ways in its lower edge, a slot-way in its upper end having its lower end enlarged, auxiliary blades having a similar slot-way in its upper end, and a vertical slot-way leading 95 therefrom through the center of the blade and adapted to engage with the aforesaid

slot-ways, a handle and a bolt engaging with said enlarged slot-ways having its upper end secured to the handle.

2. A chopping knife comprising a main blade having slot-ways in its lower end, a slot-way in its upper end, having its lower end enlarged, auxiliary blade having a similar slot-way leading therefrom through the center of the blade, said blades having the 10 upward extending part—*e*—a radially slotted

perforated disk engaging said parts, a handle and a bolt engaging with said enlarged slot-ways, and said disk, and secured to the handle as set forth.

In witness whereof I have hereunto set my 15 hand on this 18th day of July, 1893.

FRED H. RUNDELL.

In presence of—

C. W. SMITH,

HOWARD P. DENISON.
